FUEL DISTRIBUTING APPARATUS

Henry E. Lippert, Pittsburgh, Pa.

Application March 26, 1936, Serial No. 70,963

9 Claims. (Cl. 110—104)

This invention relates to stoker structure, and particularly to the fuel distributing apparatus and the construction of the discharge end of a stoker which delivers fuel to an opening in a 5 wall of a firebox.

It is customary to provide a throat, forwardly extending branch or mouth portion at the discharge or delivery end of such a stoker. In practice, a distributor head is provided at the 10 bottom of the mouth portion, and a distributor plate is arranged forwardly of the distributor head to provide a surface over which the fuel is discharged into the firebox by blasts of pressure fluid from the distributor head. The forward end of the distributor plate extends into the firebox and is exposed or subjected to a high degree of heat, causing this end of the plate to 15 burn or wear out, break away or become defective.

One of the objects of this invention is to provide a sectional distributor plate, the rear end section of which is formed with the mouth portion of the stoker, and the front end section being mounted so that it can readily and easily 20 be detached, removed and replaced without dismantling parts of the stoker, thereby reducing the time, trouble and expense in making a replacement.

Another object of the invention is the provision of new and improved means for connecting a distributor plate to a stoker conduit member, whereby the plate can be quickly and conveniently assembled at the time of replacement 25 and repair. The improvement also contemplates the provision of fuel distributing apparatus composed of a number of separable castings or members which are simple in construction, and easily and cheaply manufactured as independent units.

A further object of this invention is to provide a stoker delivery end casting or stoker conduit member of novel and improved construction. Stated more specifically, the latter object 30 consists in the provision of inclined guide surfaces on the stoker conduit member, on which guide surfaces the distributor plate can be mounted, when being assembled, and be directed downwardly into its operative position.

Other objects and advantages of the invention and detail features of construction will appear from a reading of the following description taken in connection with the accompanying drawings, forming a part hereof, in which

Fig. 1 is a vertical longitudinal section of the discharge end of a stoker and a portion of the

backhead of a locomotive firebox, showing the invention applied thereto.

Fig. 2 is a horizontal sectional view taken on line 2—2 of Fig. 1.

Fig. 3 is a vertical transverse section taken on line 3—3 of Fig. 1.

Fig. 4 is a sectional view similar to Fig. 1 and illustrates a slight modification.

Referring particularly to Figs. 1, 2 and 3, the numeral 10 designates a locomotive firebox 10 backhead or back wall having a firing opening 11 therein. The backhead is formed of an outer sheet or plate 12 and an inner sheet 13. The lower marginal wall or edge of the firing opening is shown at 14, and the side marginal walls thereof at 15 and 16. While the invention is herein shown and described as installed in a locomotive, it is to be understood that its application is not limited thereto.

A riser conduit 17 arranged parallel to the backhead comprises, generally speaking, an elevator casing 18, and a nozzle casting, hood or stoker conduit member 19 telescoped on the upper end of the elevator casing and communicating with the firing opening. The stoker conduit member 19 is formed of diverging side walls 20 and 21, a curved rear wall 22 connecting the side walls, an L-shaped flange 23 extending outwardly from each of the side walls, a top wall 29, and a bottom wall 31. The side walls 20 and 21, the top wall 29 and the bottom wall 31 form a mouth portion 32 opening forwardly into the lower part of the firing opening 11.

The riser conduit is secured at its upper end to the backhead by an angle iron 33 at each side of the firing opening. These angle irons have one leg fixed to the backhead 10 in any desirable manner, and the other leg rigidly attached to the adjacent L-shaped flange 23 on the stoker conduit member. A helical fuel transfer screw 34 in the riser conduit delivers fuel to distributing means which will now be described.

A bar-shaped distributor head 35 arranged transversely of the mouth portion 32, is seated on the bottom wall 31 forward of the helical screw 34 and rearwardly of the backhead 19. The head 35 is provided with a plurality of chambers 37 therein. Pipe lines 38 corresponding in number to the number of chambers in the distributor head, serve to deliver fluid under pressure to the chambers from any preferred source. These pipe lines extend upwardly through apertures 39 in the bottom wall 31 and are secured into the underside of the distributor head. Jet openings 40 are drilled in a hori- 50

55

zontal row in the front wall of the head 35 to communicate with the chambers 37. An upwardly projecting lug 41 is formed on each end of the distributor head, and the head is secured 5 to the side walls 20 and 21 of the mouth portion by bolts 43 which extend through these lugs.

A distributor plate, designated as a whole by the numeral 44, extends forwardly from the head 35 through the firing opening 11 adjacent 10 to and spaced slightly above the lower marginal edge 14 of the firing opening. The distributor plate 44 is formed in two sections separable from each other. A front end distributor plate section 45 is detachably connected to the stoker conduit member 19. The bottom wall 31 of the mouth portion constitutes the rear end section 15 of the distributor plate. The top surface of the front end plate section 45 lies in the same horizontal plane as the top surface of rear end plate section or bottom wall 31 and forms a forward continuation thereof. Likewise, downwardly sloping side channels 46 in the front end plate section 45 form forward continuations of similar channels 48 in the bottom wall 31. 20

25 The mouth portion bottom wall 31 extends from a point exteriorly of the firebox to a point between the outer and inner backhead sheets 12 and 13. A lip or tongue 50 formed on the forward end of bottom wall 31 is provided with an upwardly open substantially V-shaped groove 51 arranged to receive a similarly shaped flange 52 formed on the underside and at the rear end of the front end plate section 45, thereby providing an engagement between the front and rear end 30 plate sections restraining downward movement of front end plate section 45. Longitudinal movement of the front end plate section is prevented by its own weight in conjunction with the groove and flange engagement. This engagement lies approximately midway between the backhead sheets 12 and 13. The tongue 50 forms a seat for the front end plate section 45 and extends transversely thereof between the side channels 46.

45 The side walls 20 and 21 of the mouth portion extend within the firing opening and the forward edges 53 and 54, respectively, of these side walls terminate in a downwardly and forwardly inclined transverse plane. The side wall forward edges 53 and 54 are contained in the same inclined plane as the rear side of V-shaped groove 51, and they extend from a point exterior of the firebox to a point within the firing opening 11 and from the top wall 29 to the bottom wall 31. Outwardly projecting ears 55, 56 are formed 50 on side walls 20 and 21, respectively. The upper faces of these ears lie in the same inclined plane as the side wall forward edges 53 and 54. These faces of ears 55 and 56 together with the forward edges of the mouth portion side walls provide 55 on the stoker conduit member an inclined guide surface at each side of the mouth portion, upon which guide surfaces the front end plate section 45 can be placed or mounted and manually guided, directed, slid or moved downwardly and forwardly therealong into its operative position. The tongue 50 is disposed at the lower end of these inclined guide surfaces and prevents downward movement of front end plate section 45 below the plane of bottom wall 31.

70 A hook member or L-shaped lug 57 is provided on each of ears 55 and 56, and constitutes an element of an interlocking connection between the front end plate section 45 and the stoker conduit member 19. Formed on each side of

the front end plate section and at the rear thereof is an upstanding inclined arm 58. Each of arms 58 has at its upper end a laterally projecting extension lug 59 turned outwardly and arranged to engage and be received by the hook members on ears 55 and 56, thereby attaching 5 the front end plate section 45 to the stoker conduit member and preventing tilting of the front end plate section about the groove and flange engagement 51, 52. Lateral movement 10 of the front end plate section is prevented by the arms 58 engaging the inner edges of L-shaped lugs 57.

To remove a worn front end plate section it is only necessary to slide the same upwardly along 15 the inclined guide and supporting surfaces until the lugs 59 on the plate section are out of engagement with the hook shaped lugs 57 on the conduit member. The plate section can then be tilted forward, and be withdrawn through the 20 firing opening. In making the replacement, a new plate section is held so that the lower rear corner thereof will contact the inclined guide surfaces at points slightly higher than when in 25 its operative position, and so that the lugs 59 are disposed above the slots formed by the upwardly open hook shaped lugs 57. The plate section is then lowered in contact with the guide surfaces, in such manner that each lug 57 on the conduit member receives the respective lug 30 59 on the plate section, until flange 52 engages the tongue 50.

The front end plate section 45 is disposed wholly within the firebox, except for the arms 58 which extend from within the firing opening 35 11 to a point rearward of the plane of outer backhead sheet 12. The interlocking lug connections 57, 59 are thus provided where they cannot be effected by the high degree of heat in the firebox. Should the tongue 50 burn or break 40 away due to the heat in the firebox, the L-shaped lugs 57 will then vertically support the front end plate section in a hinged relation to the stoker conduit member, the very slight vertical clearance or space between lugs 57 and 59 45 preventing the front end plate section 45 from moving downwardly a distance sufficient to render the device inoperable.

Strengthening ribs 60 between the front end plate section 45 and the arms 58 form forward 50 continuations of the side walls 20 and 21. These ribs prevent fuel discharged over the distributor plate 44 by pressure fluid blasts from jet openings 40 from striking the side marginal walls 55 and 16 of the firing opening.

In the modification shown in Fig. 4, a wearing sheet 61 is removably attached to the top surface of bottom wall 62 as by means of a screw 63. In all other respects the modified form is the same as that described herein.

I claim:

1. In a stoker, a conduit member having a mouth portion provided with a downwardly and forwardly inclined surface at each side thereof, a distributor plate arranged to receive fuel for distribution over a fire, said inclined surfaces being disposed to engage the rear edge of said distributor plate and thereby direct it into its operative position, means detachably connecting said distributor plate and said conduit member, and means for discharging fuel over said distributor plate.
2. In a stoker, the combination with a firebox provided with a firing opening, a conduit member having a mouth portion in communica- 75

tion with said firing opening, said mouth portion being provided with a downwardly and forwardly inclined surface at each side thereof, a distributor plate extending forwardly from beneath said mouth portion and arranged to receive fuel for distribution over a fire, said inclined surfaces extending from without to within said firing opening and being disposed to engage the rear edge of said distributor plate and thereby direct it into its operative position, means detachably connecting said distributor plate and said conduit member, and means for discharging fuel over said distributor plate.

3. In a stoker, a conduit member having a mouth portion provided with a downwardly and forwardly inclined surface at each side thereof, a distributor plate arranged to receive fuel for distribution over a fire, inclined arms on said distributor plate arranged to slidably engage said inclined surfaces, said inclined surfaces being contained in a common plane and disposed to engage the rear edge of said distributor plate and thereby direct it into its operative position, means detachably connecting said distributor plate and said conduit member, and means for discharging fuel over said distributor plate.

4. In a stoker, a conduit member having a mouth portion provided with a downwardly and forwardly inclined surface at each side thereof, and a distributor plate extending forwardly from beneath said mouth portion and arranged to receive fuel for distribution over a fire, said inclined surfaces being disposed to engage the rear edge of said distributor plate and thereby direct it into its operative position, said conduit member and said distributor plate each being provided with an element of an interengaging means, one of said elements being provided on one of said inclined surfaces and arranged to engage the other of said elements, and means for discharging fuel over said distributor plate.

5. In a stoker, a conduit member having a mouth portion provided with a downwardly and forwardly inclined surface at each side thereof, a distributor plate arranged to receive fuel for distribution over a fire, said inclined surfaces being disposed to direct said distributor plate into its operative position, an arm on each side of said distributor plate arranged to slidably engage one of said inclined surfaces, a lug on each of said inclined surfaces disposed to engage the respective arm on said distributor plate, and means for discharging fuel over said distributor plate.

55 6. In a stoker, a conduit member having a mouth portion provided with an inclined surface at each side thereof, a distributor plate arranged to receive fuel for distribution over a fire, said inclined surfaces extending from the top to the bottom of said mouth portion in a

downwardly and forwardly direction and being disposed to engage the rear edge of said distributor plate and thereby direct it into its operative position, means on said inclined surfaces arranged to engage said distributor plate for detachably connecting the latter to said conduit member, and means for discharging fuel over said distributor plate.

7. In a stoker, a conduit member having a mouth portion provided with a bottom wall constituting the rear end section of a distributor plate, said conduit member also having a downwardly and forwardly inclined surface at each side of said mouth portion, a front end distributor section forming with said bottom wall a distributor plate arranged to receive fuel for distribution over a fire, said inclined surfaces being disposed to engage the rear edge of said front end distributor section and thereby direct it into its operative position, said front end distributor section being provided at each side of its rear end with an element of interengaging means detachably connecting said front end distributor section and said conduit member, an upwardly open hook shaped lug on each side of said conduit member forming the other elements of said interengaging means, and means for discharging fuel over said distributor plate.

8. In a stoker, a conduit member having a mouth portion provided with a bottom wall, a front end distributor section forming with said bottom wall a distributor plate arranged to receive fuel for distribution over a fire, means for directing said front end distributor section into its operative position, said front end distributor section being provided on each side of its rear end with an interengaging element, an upwardly open hook shaped lug on each side of said conduit member forming the other interengaging elements, each of said lugs being arranged to receive the respective interengaging element on said front end distributor section upon downward movement of the latter into its operative position, and means for discharging fuel over said plate.

9. In a stoker, a distributor plate having a horizontal top surface arranged to receive fuel for distribution over a fire, a member at the delivery end of the stoker provided with a spaced pair of guide surfaces disposed to engage the rear edge of said distributor plate and thereby direct it into its operative position, said guide surfaces extending above the horizontal top surface of said distributor plate, an upstanding arm on said distributor plate, means on said member arranged to engage said arm upon downward movement of said distributor plate into its operative position, and means for discharging fuel over said distributor plate.

HENRY E. LIPPERT. 60
